GARMENT HANGER

Otto Gebhardt, New York, N. Y.

Refiled for abandoned application Serial No. 645,174, December 1, 1932. This application March 11, 1936, Serial No. 68,338

2 Claims. (CL 223—86)

This application is filed as a substitute for abandoned application, Serial Number 645,174, filed December 1, 1932.

This invention relates to devices for supporting garments and more particularly to such as are commonly called coat hangers.

In such devices it is usual to present a bar curved arcuately from end to end in conformity with the shoulders of an individual and smoothly rounded in cross section, at least at its upper surface.

Sometimes a straight chordal bar extends from end to end below the curved raised portion, over which may be supported folded articles of personal wear, as for instance trousers and set in the center of the hanger, to extend upwardly, is a hook or clip to engage over a fixed support.

It is an object of this invention to provide a metallic hanger, made from a tube of circular cross section, whereby smoothly rounded surfaces are presented and additionally, a structure in which unusual strength is combined with lightness in weight.

A further feature is in the provision of means by which the straight horizontal support bar may be detachably engaged with the hanger, thereby facilitating the disposal of articles thereon or removal of the same.

Another purpose is to produce a hanger adapted to be supplied with tablets composed of material offensive to moths and like insects injurious to clothing.

These and analogous aims and objects are attained by the novel construction and arrangement of parts hereinafter described and shown in the accompanying drawing, forming a material part of this disclosure, and in which:—

Figure 1 is a longitudinal sectional view of an embodiment of the invention in its simple form.

Figure 2 is a transverse sectional view taken on line 2—2 of Figure 1.

Figure 3 is a view similar to Figure 1, but showing a horizontal support bar combined therewith.

Figure 4 is a transverse sectional view taken on line 4—4 of Figure 3.

Figure 5 is a longitudinal sectional view of the preferred form of hanger.

Figure 6 is a perspective view of the combined caps and hinged connection.

Figure 7 is a similar view of the opposite cap and extending clip.

Figure 8 is a perspective view of the detachable end of the straight bar.

Throughout the several views the numeral 10

designates in general a metallic tube, curved in conformity with the shoulders of an individual and having a longitudinal opening 11 in its under, concave side.

Set centrally in the tube is a block 12 to engage the inner end of a stem 13 extending upwardly through the tube and terminating in a hook 14 to engage any convenient support, as within a closet or the like where the clothing is to be placed.

The extreme ends of the tube are preferably flared slightly outward, as at 15, to engage caps 16 having bevelled annular flanges 17 adapted to be pressed over the ends of the tube to be retained by the flared members, but may be withdrawn, due to the wall of the split tube yielding upon the application of moderate force.

This feature permits the tube to be supplied with a disinfectant, as the moth balls 18 shown.

In Figure 3 the tube 10 has inserted at its ends, adjacent the caps 16, a rod, bar or smaller support tube 19, having spherical ends 20 to retain it in place, the rod 19 adapted to receive the flat folded articles thereover.

Figure 5 shows a cap 16 of similar construction but connected by a hinge 21 with another similar cap 16' having a flange 17' to engage over the slightly expanded end of a straight tube 22, split as at 23, and adapted to contain similar moth balls 18.

The opposite end of the straight tube 22 is closed and formed to produce a tongue 24 suited to engage a spring clip 25 fixed to extend at an angle downwardly from the cap at the corresponding end of the bowed tube 10, thereby rendering said end of the bar 22 readily detachable when entering or removing articles.

From the foregoing it will be seen that a simple device for this purpose has been disclosed in the preferred form of its embodiment, but it is not desired to restrict the details to the exact constructions shown, it being obvious that changes may well be made without departing from the spirit and scope of the invention in its broadest aspect.

Having thus described the invention, what is claimed as new and desired to secure by Letters Patent, is:

1. A coat hanger comprising a bowed cylindrical tube split throughout its length at its underside, a support hook fixed in said tube, said tube being expanded at its ends, caps having flanges to engage over the expanded ends of said tube, a straight split cylindrical tube having one expanded end, a cap thereon, hinged connections 50 55

between one of the caps on said bowed tube and the cap on said straight tube, and means on the opposite end of said straight tube to detachably engage the opposite end of said bowed tube.

5. 2. A coat hanger comprising a bowed cylindrical tube split throughout its length at its underside, said tube being expanded at its ends, a support hook fixed in said tube, caps having flanges to detachably engage over the expanded ends of said

tube, a straight split cylindrical tube having one expanded end provided with a cap, a hinge connecting the last named cap with the cap on the adjacent end of the bowed tube, a spring clip fixed on the cap at the opposite end of said bowed tube, and a tongue formed on the free end of said straight tube to engage in said spring clip. 5

OTTO GEHARDT.
